UNITED STATES PATENT OFFICE.

SAMUEL L. WORSLEY, OF TAUNTON, MASSACHUSETTS, ASSIGNOR TO THE BROWN & SHARPE MANUFACTURING COMPANY, OF PROVIDENCE, RHODE ISLAND.

STOP-MOTION FOR LATHES.

SPECIFICATION forming part of Letters Patent No. 398,871, dated March 5, 1889.

Application filed July 9, 1888. Serial No. 279,380. (No model.)

To all whom it may concern:

Be it known that I, SAMUEL L. WORSLEY, of Taunton, in the county of Bristol and Commonwealth of Massachusetts, have invented 5 certain new and useful Improvements in Stop-Motions for Lathes; and I do hereby declare that the following specification, taken in connection with the drawings making a part of the same, is a full, clear, and exact description thereof.

Figure 1 is a vertical transverse section of an engine-lathe on the line A B of Fig. 3. Fig. 2 is a view, partly in section and partly in elevation, showing the tripping-latch. Fig. 15 3 is a front view of a portion of an engine-lathe. Figs. 4 to 8, inclusive, represent details.

Stop-motions for lathes have long been in use, and generally consist in a combination 20 of devices which operate to cause a belt-shuttle to be moved at the required time to run the driving-belt from the fast to the loose pulley.

My improvement consists in an improved 25 combination of devices whereby at an appointed time the movement of the tool-carrying carriage shall be instantly stopped by disconnecting the carriage from the source of power which moves it, while the other parts 30 of the lathe may continue in operation until it is convenient to shift the driving-belt and stop the entire machine.

In the accompanying drawings, 2 (in Figs. 1, 2, and 3) is the ordinary traveling bed of 35 an engine-lathe upon which the tool-holder, adapted to slide at right angles therewith, is mounted. Motion is given to this bed or carriage when the lathe is at work for turning by means of the worm 9, Fig. 3, revolving with 40 the screw-shaft 8, with which it is connected by means of a groove and spline, so as to traverse the shaft, but revolve with it. This worm 9 engages with the worm-wheel 13, Figs. 1 and 2, whereby, through the pinion 10 45 on the same shaft, motion is given to the intermediate gear, 12, Fig. 3, and its pinion 11 gives the proper movement to the bed 2 through the rack 7, with the teeth of which

the said pinion 11, set fast on said gear-wheel 12, engages.

The leading-screw 8, which is shown at Fig. 3, and which is in constant revolution when the driving-belt is on the fast pulley, is used when the lathe is employed for cutting screw-threads; but it may be disregarded in the 55 present combination, in which the movement of the carriage 2, when carrying a turning-tool, is not obtained from such screw, but from the worm and train of gearing above described. Said leading-screw derives its 60 motion from the head-spindle of the lathe through a train of connecting-gears in a common way.

The worm-wheel 13, driven, as above stated, by the worm 9, is loosely mounted on its hollow sleeve-shaft, as shown in section at Fig. 1; but the pinion 10, Figs. 1 and 2, is fixed to the same sleeve. If the worm-wheel 13 be prevented from revolving on its shaft, then it will connect the constantly-revolving worm 70 9 with the train of gears 10, 12, and 11 and the rack 7, and give movement to the carriage 2. If, however, it be allowed to revolve freely on its shaft, no movement will be given to the carriage.

The worm-wheel 13 is capable of being locked to its shaft by means of a friction-clutch. (Shown at Fig. 6.) The back side of the worm-wheel is cored out, as shown at Fig. 1, so as to form a flange. Against the inner 80 face of this flange is placed a divided ring, 23, Fig. 6. This ring can be expanded to a larger diameter by means of wedges 25, when the same are forced into the joints between the sections of the ring. These wedges 25 (of 85 Fig. 6) are shown in section at Fig. 1. They form, with the part marked 26, bell-crank levers, and are mounted in a holder, Fig. 5, which is keyed to the shaft 14, Fig. 1, and stands arranged relatively to the worm-wheel 90 13, as shown in section at Fig. 1. The wedges 25, or shorter arms of the bell-cranks, are made, preferably, adjustable in position relatively to the longer arms, 26, by means of adjusting-screws 27, such shorter arms being 95 pivoted to the longer arms and having shoul-

ders against which the ends of the adjusting-screws 27 can bear. The object of this adjustability is to compensate for the wearing away of the faces of the wedge 25.

5 It is obvious that whenever the longer arms, 26, of the bell-crank levers are moved toward the left (looking at Fig. 1) the faces of the wedges 25 will be moved radially outward, and, entering the joints between the sections 10 of the friction-ring 23, will spread the sections apart and cause them to act as a powerful friction-clamp against the interior face of the flange of worm-wheels 13. This movement for this purpose is effected by the operator of 15 the machine when he raises the quadrant-shaped lever 32, Fig. 2, by means of its handle. This lever is keyed to a shaft, 22, which carries a yoke or fork, 19, the cross-bars of which engage with a groove, 21, in the central rod, 40, Fig. 1. Now the ends of the longer arms, 26, of the bell-cranks enter a slot or mortise in this rod, and consequently when the operator raises the quadrant-lever 32 the friction-brake will be applied to stop the separate revolution 25 of the worm-wheel 13. It is very desirable that the rod 40 should be seated against a spring, 16, the strength of which can be regulated by an adjusting-screw, 17, so that upon the tripping of the latch, hereinafter to 30 be mentioned, for holding the quadrant-lever 32 the wedges will be instantly withdrawn from their action on the friction-ring 23, and the worm-wheel 13 be free to revolve on its shaft.

35 The effect of moving the quadrant-lever 32 to the position shown at Fig. 2 being to bring the friction-clutch above described into action, it follows that the worm-wheel, the sleeve upon which it is loosely mounted, the pinion 40 10, fast to such sleeve, and the shaft 14 will be revolved as one, and by means of the gears 12 and 11 and the rack 7 movement will be given to the carriage 2.

The lever 32 is held in position by the catch-lever 33, Fig. 2, and so long as the machine is 45 in this condition and power is applied to the driving-pulley the carriage 2, which carries the tool-post, will be traveling.

To effect the instantaneous stopping of the 50 cutting of the tool in turning a piece of metal at a predetermined place, a stop-pin, 31, Fig. 3, having an inclined or conical end, is set in a block, 28, which block can be adjusted in position on the lathe-bed by means of a set-screw, 30. A fine adjustment in addition can 55 be made by turning the stop-pin to the right or to the left, its shank where it enters the

block 28 being screw-threaded for that purpose.

When the carriage has advanced so far that 60 the catch-lever 33 comes into contact with the conical end of the stop-pin 31, the lever will be raised by the progressive movement of the carriage, causing the lever to ride up the cone or incline, and thereupon a disconnection will 65 be effected between the driving-worm 9 and the train which moves the tool-carriage, while at the same time the spindle of the lathe may continue to revolve.

It will be seen that by the means above described a disconnection between the source of power and the carriage carrying the cutting-tool is capable of being effected with certainty and without any liability of any dragging or sluggishness in action. The gradual 75 upward movement of the catch-lever 33 does not act as does the gradual separation of the two parts of an ordinary clutch-box connection, by which the continuity of trains of gearing is broken. It is not until the catch 80 has released the lever 32 that the disconnection is made, and it then is instantaneous. This capacity is of prime importance in saving the necessity of close personal supervision in turning certain varieties of work—as, for 85 instance, in turning a rod up to a shoulder on the same or the shank of a bolt up to its head.

What I claim as my invention, and desire to secure by Letters Patent, is—

1. The combination, substantially as hereinbefore set forth, of a worm driven by the power which drives the head-spindle of the lathe, a worm-wheel driven by said worm, a friction-clutch for connecting said worm-wheel with the train which communicates movement to the tool-carriage or for disconnecting it therefrom, a lever for working said friction-clutch, a holding-catch for locking the lever to close the clutch, a sliding tool-post carriage, and a stop for tripping the holding-catch, substantially as described. 90

2. The combination of a friction-clutch connecting the train of gearing which gives movement to the tool-carriage with the prime mover, a lever for working said clutch to make or break such connection, a holding-catch for locking the lever to close the clutch, a sliding tool-post carriage, and a stop for tripping the holding-catch, substantially as described. 95 100 105
